UNITED STATES PATENT OFFICE.

LIONEL M. WOLFSOHN, (NOW BY JUDICIAL CHANGE OF NAME LIONEL M. WOOLSON,) OF HOBOKEN, NEW JERSEY, ASSIGNOR, BY MESNE ASSIGNMENTS, TO BIJUR MOTOR APPLIANCE COMPANY, A CORPORATION OF DELAWARE.

ENGINE-STARTING APPARATUS.

1,393,595.

Specification of Letters Patent. Patented Oct. 11, 1921.

Application filed August 2, 1916. Serial No. 112,662.

To all whom it may concern:

Be it known that I, LIONEL M. WOLFF-
SOHN, (now by judicial change of name
LIONEL M. WOOLSON,) a citizen of the United
5 States, and a resident of Hoboken, in the
county of Hudson and State of New Jersey,
have invented an Improvement in Engine-
Starting Apparatus, of which the following
is a specification.

10 This invention relates to engine-starting
apparatus, and with regard to certain more
specific features, to motor-operated engine-
starters in which a motor-driven member is
shifted into and out of connection with the
15 engine. The present invention is an im-
provement on certain inventions of Joseph
Bijur, set forth in his United States Patent
No. 1,095,696, dated May 5, 1914, for engine
starting apparatus and in his United States
20 application, Serial No. 79,025, filed February
18, 1916, for engine starting apparatus.

One of the objects of the invention is to
provide starting apparatus for internal com-
bustion engines, which shall be of simple
25 construction and efficient and reliable action.
Another object is to provide a simple and
compact engine-starting apparatus in which
the danger of damaging the parts by jam-
ming or otherwise, is minimized or elimi-
30 nated.

Another object is to provide improved ap-
paratus of this general type, in which one of
two gears relatively movable axially, is auto-
matically forced into meshing condition in
35 case the teeth of the two gears tend to meet
end to end.

Another object is to provide a mechanism
of the above general type in which the parts
are arranged and proportioned to minimize
40 the external dimensions of the apparatus
without sacrifice of mechanical strength or
low cost of construction.

Another object is to provide an inexpen-
sive and efficient construction of the above
45 nature enabling the parts to be easily assem-
bled and readily disassembled in case of
inspection or repair.

Other objects will be in part obvious, and
in part pointed out hereinafter.
50 The invention accordingly comprises the
features of construction, combinations of ele-
ments and arrangements of parts which are
exemplified in the structure hereinafter de-

scribed, and the scope of the application of
which will be indicated in the following 55

In the accompanying drawings, in which
is shown one of various possible embodi-
ments of this invention,

Figure 1 is a longitudinal elevation of a 60
preferred type of motor starter made in ac-
cordance with the present invention, with
portions of the motor and engine illustrated
conventionally, and the motor-driven pinion
and engine-driven gear shown in disengaged 65
position.

Fig. 2 is a sectional elevation on the line
2-2 of Fig. 1, showing the elongated pinion
on the motor shaft, the gear driven thereby,
and associated parts. 70

Fig. 3 is a fragmentary longitudinal eleva-
tion similar to the right-hand portion of
Fig. 1, but showing the motor-driven pinion
and engine-driven gear partially in mesh.

Fig. 4 is a view similar to Fig. 3, showing 75
the relation of the several parts when the
teeth of the motor-driven pinion and engine-
driven gear meet end to end.

Similar reference characters indicate simi-
lar parts throughout the several views of 80
the drawings.

This invention relates to apparatus for
starting engines such as internal combustion
engines, which are ordinarily incapable of
starting without the assistance of external 85
power. In a preferred form of the inven-
tion, the fly-wheel of the engine is provided
with a gear, which, at appropriate times, is
meshed with a pinion driven from an elec-
tric motor. To start the engine, power is 90
applied to the motor, and the rotation of the
motor effects both the meshing of pinion and
gear and the rotation of the engine shaft
through the medium of the pinion and gear.

When the engine has started to rotate under 95
its own power, the pinion and gear are dis-
engaged by an action similar to that shown
in above-mentioned Patent No. 1,095,696,
dated May 5, 1914, and the power is cut off
from the motor either manually or auto- 100
matically, as may be desired, these features
of construction in themselves forming no
part of the present invention.

Referring now to the accompanying draw-
ings, there is shown in Fig. 1 an engine 1 105
comprising a casing 2 and shaft 3, upon

which is mounted a fly-wheel 4, carrying a gear 5, hereinafter referred to as the engine-driven or fly-wheel gear. A motor shown conventionally at 6, has mounted upon its shaft 7 an elongated pinion 8 meshing with the gear 9 mounted at 10 on a countershaft 11 for rotation and axial movement with respect to said countershaft. The left end of the countershaft has a bearing at 12 in the frame 13 of the motor 6, while the right end of the countershaft is provided at 14 with a bearing formed in an extension 15 of the motor frame; suitable lubricating devices are provided for these bearings and in other portions of the apparatus where they may be needed, but since the lubrication forms no feature *per se* of the present invention, these devices are indicated only diagrammatically, and in some instances are not shown at all in the accompanying drawings.

The gear 9 is provided with an annular recess 16 to receive a comparatively heavy compression spring 17, the opposite end of which bears against a collar 18 mounted on the countershaft 11 but prevented from leftward axial movement thereon, by the shoulder 20. It will thus be seen that rotation of the motor causes the gear 9 to rotate, being pressed rightward axially of the countershaft 11, by means of the heavy compression spring 17.

The rightward movement of the gear 9 is opposed by a friction disk 22 riveted as at 24 to the disk 25, which in turn abuts a spacing washer 27 integral with a collar 29 axially slotted as at 30, to receive a pin 31 passing through the slots 30 and through a diametrical aperture 32 in the countershaft 11. The heavy compression spring 17 normally forces the gear 9, friction disk 22, disk 25 and collar 29 rightward, and holds these parts in the axial position illustrated in Fig. 1, with the pin 31 at the left end of the longitudinal slot 30, that is, with the pin 31 bearing against the right face of the spacing washer 27. A thin snap cylindrical cover, shown conventionally at 33, serves to retain the pin 31 in position with respect to the countershaft 11. The right-hand face 34 of the gear 9 is thus forced axially rightward by the compression spring 17, against the friction disk 22 so that the rotation of the motor shaft 7, pinion 8 and gear 9 acts through this friction clutch 34-22 to transmit any torque of a moderate value, to the friction disk 22, and thus to the disk 25 riveted thereto, whence this torque is transmitted through the feather-key drive indicated conventionally as a flat on the shaft at 35, to the countershaft 11. That is, if the load upon the countershaft is less than the torque-transmitting capacity of the clutch 34-22, the countershaft will be rotated at the same speed as the gear 9.

The rotation of the countershaft 11 effects

the operation of the fly-wheel gear 4. For this purpose, the countershaft 11 is externally screw-threaded, as at 37. Mounted upon this screw-threaded portion of the countershaft, for rotation and axial movement with respect thereto, is a pinion 38, hereinafter referred to as the sliding or motor-driven pinion. This pinion is provided with internal screw-threads 39 registering with the external screw-threads 37 of the countershaft 11. From this it will be clear that if there is relative rotation between countershaft and pinion, there will be relative axial movement between these two elements, owing to the screw-threaded connection between them; and conversely, if relative rotation be prevented, relative axial movement will likewise be prevented. In the operation of the apparatus, power is applied to the motor to set its shaft 7, and gear 9 in rotation; this transmits motion to the gear 9 and countershaft 11. The pinion 38 does not at once acquire the speed of rotation of the countershaft 11, due to the inertia of said pinion. Thus the countershaft 11 rotates faster than the pinion 38, and this relative rotation of countershaft and pinion causes the latter to travel axially of the former, toward the left in Fig. 1, and into engagement with the teeth 40 of the fly-wheel gear 5. The teeth 41 of the motor-driven gear 38 preferably have their ends toward the fly-wheel tapered, so that unless the teeth meet almost exactly end to end, said teeth will satisfactorily mesh with one another, the tapered surfaces effecting a slight rotation of the pinion, if necessary, to insure the meshing of teeth. Usually, in the operation of the starting apparatus, the pinion 38 and gear 5 will be brought into mesh without difficulty, either with or without the aid of these tapered surfaces of the teeth, and the operation thereafter will be as indicated below under the heading "Operation after meshing". However, the teeth 41 might jam against the teeth 40, and in order to prevent the trouble that would ensue in such a case, the present invention includes among its advantageous features the provision of certain constructions and operation of parts, a preferred embodiment of which will be hereinafter described under the heading "Operation to enforce meshing".

It will be noted that the apparatus as a whole is compactly arranged. Particularly, the gear 9 is provided with the annular recess 16 to receive the spring 17, and the spring 45 extends over the elongated bearing 14 for the sliding countershaft 11 for a considerable distance axially of the countershaft, thereby economizing in space lengthwise of the apparatus. The pinion 38 preferably travels inwardly toward the motor into engagement with the fly-wheel gear, rather than outwardly into such engagement, thus reducing the various strains attendant upon the crank-

ing of the engine and rendering the apparatus more compact.

Operation prior to meshing.—When the engine is to be started, power is applied to the motor, to set its shaft 7 and pinion 8 in rotation. This rotates gear 9, friction disk 22, and countershaft 11. The pinion 38 does not at once acquire the speed of rotation of the countershaft 11, owing to the inertia of the pinion or its friction against the cupped washer 42 or other means. This relative rotation of countershaft and pinion, the former at a higher speed than the latter, causes the pinion to travel to the left until its teeth 41 reach the teeth 40 on the gear 5 mounted upon the fly-wheel 4 of the engine 1.

Operation after meshing.—Ordinarily, the teeth 40 and 41 will mesh, and the pinion 38 will then travel leftward to and past the position shown in Fig. 3 of the drawings into full mesh. When the left face 43 of the pinion strikes the right face of the collar 29, the leftward travel of the pinion is cushioned by the compression spring 17.

If, as is ordinarily the case, the engine cannot be started without the use of a greater torque than that afforded initially at the friction clutch 34—22, the pinion does not rotate, but instead the continued rotation of the countershaft 11 causes the pinion to travel still further leftward, thereby compressing the clutch members 34—22 against the force of the spring 17, and automatically tightening the clutch by increasing the coefficient of friction between its coöperating surfaces. When gear 9 strikes collar 18 the leftward movement of the former is stopped and the clutch members quickly jammed together. This increases the torque of the clutch to a point where the clutch can transmit the power needed to drive the engine, and the engine is started.

When the engine has begun to rotate under its own power, disengagement of the fly-wheel gear 5 and the motor-driven pinion 38 is effected as follows:—The pinion 38, now driven from the gear 5 instead of driving it, rotates faster than the motor-driven countershaft 11, and with this excess of speed the pinion travels along the countershaft toward the right, out of engagement with the gear 5, regardless of whether the motor has stopped or is still running. As the pinion 38 approaches the rightward limit of its travel, its right face engages frictionally the cupped washer 42 abutting the shoulder 47 on the countershaft 11 and tending to maintain the shaft in its leftward position, and compresses the comparatively light compression spring 45 mounted between this cupped washer 42 and the seat 46 in the extension 15 of the motor frame 6. This deadens the movement of the pinion 38 and prevents the pinion from rebounding

into mesh with the gear. By this time the power may be shut off in the motor, and the motor-driven countershaft comes to rest. The friction between the pinion 38 and cupped washer 42 offers enough resistance to the movement of the pinion so that the pinion when in its right-hand position of rest, does not rotate without appreciable torque, and hence this spring and washer act as a detent and serve to prevent the accidental rotation of the pinion 38 and the consequent possible contacting of gear and pinion, owing to the vibration of the apparatus when the engine or vehicle is running.

Operation to enforce meshing.—In case the pinion teeth 41 should jam against the fly-wheel-gear teeth 40, the pinion will be unable to travel farther toward the left, and since the countershaft is at this time rotated by the motor there will be considerable end-thrust toward the right, upon the countershaft, since said countershaft is unable to push the pinion axially toward the left. The rightward movement of the countershaft 11 is opposed by the compression of the relatively light coil spring 45 mounted between the cupped washer 42 and the seat 46. As the countershaft 11 moves toward the right, the countershaft carries with it the left-hand collar 18 hereinbefore described as abutting against a shoulder 20 on the countershaft and receiving the left end of the heavy spring 17, whose other end bears against the gear 9. This rightward movement of the countershaft 11 does not at first increase the torque of the friction clutch 34—22, but as soon as the right face 44 of the collar 29 strikes the left face 43 of the pinion 38, the clutch 34—22 is compressed, and the frictional contact between collar and pinion, or the increased friction at the pinion threads 39, or both, causes the pinion to rotate slightly, enough to bring the pinion teeth 41 into mesh with the fly-wheel-gear teeth 40. Then the light spring 45, which at this time is under considerable compression, forces the countershaft 11, and with it the pinion 38, leftward so that the pinion is thus brought fully into mesh with the fly-wheel gear 5. In this way the jamming or rather the incipient jamming, of the teeth of pinion and gear is almost instantaneously relieved, and any damage to the parts of the apparatus is prevented by the prompt relief afforded by the coöperation of the light spring 45 and associated parts.

It may be noted that by this arrangement of using a light spring 45 in conjunction with the relatively heavy spring 17, there is a complete cushioning of the shock occasioned not only by the leftward axial movement of the countershaft, but the application of torque to the pinion to relieve the jamming condition is also gradual. And

this is accomplished without sacrificing the heavy spring action when the clutch is tightened in cranking the engine.

After the slight rotation of the pinion 38 to relieve the incipient jamming condition, its leftward movement is no longer opposed by the fly-wheel-gear teeth 40, and the pinion is shifted toward the left by the expansion of the light spring 45, as above described. The teeth 40 and 41 of gear and pinion are thus brought into mesh, and further rotation of the motor serves to cause the operation described under the heading "Operation after meshing" in the same manner as if no incipient jamming had occurred.

From the above, it will be seen that there is provided apparatus in which the objects of the invention are realized, and other advantageous results obtained.

As various changes might be made in the above construction, and as the above invention might be embodied in different forms, it is intended that all matter set forth in the above description and in the accompanying drawings, shall be interpreted as illustrative and not in a limiting sense.

Having thus revealed this invention, I claim as new and desire to secure the following combination of elements, or equivalents thereof, by Letters Patent of the United States:

1. In apparatus of the class described, in combination, an engine, a motor, an engine-driven gear, a friction clutch, a pinion driven from said motor through said friction clutch and axially movable into mesh with said gear, an axially movable member upon which said pinion is mounted, means adapted to exert a cushioning effect to cushion and limit the axial movement of the pinion into engagement with the gear, and means for tightening the clutch when engagement has been effected.

2. In apparatus of the class described, in combination, an engine-driven gear, a motor, a friction clutch, a threaded member driven from said motor through said friction clutch, a pinion threaded on said member in position to travel on its threads into mesh with said gear, and means engaging the entering end of said pinion to tighten said clutch and thereby apply an increasing rotary force to said pinion upon the teeth of said pinion meeting those of said gear end to end.

3. In apparatus of the class described, in combination, an engine, a motor for starting the same, a driving connection between engine and motor including a friction clutch and including normally disengaged gears relatively movable to bring the teeth of said gears into mesh, and means for automatically tightening said clutch and effecting relative rotation of said gears to bring them into mesh when their teeth meet end to end.

4. In apparatus of the class described, in combination, an engine, a motor for starting the same, a driving connection between engine and motor including a friction clutch and a normally disengaged gear and pinion 70 relatively movable to bring the teeth of gear and pinion into mesh, and means acting automatically, upon the jamming of pinion teeth against gear teeth, to increase the torque of said clutch and rotate the pinion 75 into mesh with the gear.

5. In apparatus of the class described, in combination, an engine, a motor, a gear connected to the engine, a friction clutch, a pinion driven by the motor through said 80 friction clutch, means whereby the pinion is moved into engagement with the gear during the starting operation, and means for automatically tightening said clutch and simultaneously rotating the pinion when the 85 pinion teeth and the gear teeth meet end to end.

6. In apparatus of the class described, in combination, an engine, a starting motor therefor, a driving connection between engine and motor, including a clutch operating with a moderate torque, and including a normally disengaged gear and pinion relatively movable axially to bring the gear teeth and pinion teeth into mesh, and means 90 acting automatically upon an incipient jamming of gear teeth against pinion teeth end to end, to increase said torque and thereupon to effect a relative rotation of gear and pinion to bring said gear teeth and pinion teeth 95 into mesh.

7. In apparatus of the class described, in combination, an engine, a starting motor therefor, an engine-driven gear, a yieldable clutch, a pinion driven from said motor 105 through said yieldable clutch, said pinion being shiftable axially into and out of engagement with said gear, and means effective after the meshing of gear teeth and pinion teeth for limiting the axial movement of the 110 pinion and simultaneously forcing said pinion to rotate, said means being automatically effective to tighten said clutch and force the rotation of the pinion when the pinion teeth and gear teeth meet end to end. 115

8. In apparatus of the class described, in combination, an engine, a motor, an engine-driven gear, a friction clutch, a pinion slideable axially into and out of engagement with said gear and driven from said motor 120 through said friction clutch, means for limiting the axial movement of the pinion into engagement with the gear, and means for frictionally engaging the pinion and simultaneously tightening said clutch to rotate 125 the pinion when during a starting operation the pinion teeth and gear teeth meet end to end.

9. In apparatus of the class described, in combination, an engine, a motor, an engine- 130

- driven gear, a friction clutch, a pinion driven from said motor through said friction clutch and axially movable into mesh with said gear, an axially movable member upon which said pinion is mounted, means adapted to exert a cushioning effect to cushion and limit the axial movement of the pinion into engagement with the gear, and means offering resistance to relative axial shifting of said member and said pinion during the jamming of the teeth and for effecting a frictional drive between said member and said pinion to rotate the pinion and thereby break said jam.
10. In apparatus of the class described, in combination, an engine, a motor, an engine-driven gear, a friction clutch, a pinion driven from said motor through said friction clutch and axially movable into mesh with said gear, a member on which said pinion is mounted, and means adapted to exert a relatively light cushioning effect to cushion and limit the axial movement of the pinion into engagement with the gear, said means offering a resistance to relative axial shifting of said member and said pinion during the jamming of the teeth and for increasing the torque of said clutch, whereby a frictional drive between said member and said pinion is effected to rotate the pinion and break said jam.
11. In apparatus of the class described, in combination, an engine, a motor for starting the same, a driving connection between engine and motor including a friction clutch and including normally disengaged gears relatively movable to bring the teeth of said gears into mesh, means for automatically effecting relative rotation of said gears to bring them into mesh when their teeth meet end to end, and means for automatically tightening said clutch as the gears mesh.
12. In apparatus of the class described, in combination, an engine, a motor for starting the same, a driving connection between engine and motor including a friction clutch and a normally disengaged gear and pinion relatively movable to bring the teeth of gear and pinion into mesh, means acting automatically upon the jamming of pinion teeth against gear teeth to rotate the pinion into mesh with the gear, and means acting automatically when the gear and pinion have meshed, to increase the torque of said clutch.
13. In apparatus of the class described, in combination, an engine, a motor, an engine-driven gear, a friction clutch, a pinion driven from said motor through said friction clutch and axially movable into mesh with said gear, an axially movable member upon which said pinion is mounted, means adapted to exert a cushioning effect to cushion and limit the axial movement of the pinion into engagement with the gear, means offering a resistance to relative axial shifting of sleeve and pinion during the jamming of the teeth whereby a frictional drive between sleeve and pinion is effected to rotate the pinion and thereby break said jam, and means for tightening the clutch automatically up to a degree at which the members are jammed together when engagement has been effected.
14. In apparatus of the class described, in combination, an engine-driven gear, a motor, a friction clutch, a threaded member driven from said motor through said friction clutch, a pinion threaded on said member in position to travel on its threads into mesh with said gear, and means engaging the entering end of said pinion adapted to apply a rotary force to said pinion upon the teeth of said pinion meeting those of said gear end to end, and to tighten said clutch when the gear and pinion have meshed.
15. In apparatus of the class described, in combination, a shaft provided with a shoulder, a compression spring surrounding said shaft, a collar abutting said shoulder and adapted to receive said spring, a gear on said shaft annularly recessed to receive the other end of said spring, and a friction device keyed to said shaft, said device co-operating with a face of said gear to form a friction clutch.
16. In apparatus of the class described, in combination, a shaft provided with a shoulder, a compression spring surrounding said shaft, a collar abutting said shoulder and adapted to receive said spring, a gear on said shaft annularly recessed to receive the other end of said spring, a friction device keyed to said shaft and adapted for limited movement axially of said shaft, said device co-operating with a face of said gear to form a friction clutch, and means for forcing said friction member axially of the sleeve in a direction to tighten the clutch.
17. In apparatus of the class described, in combination, a shaft provided with a shoulder, a compression spring surrounding said shaft, a collar abutting said shoulder and adapted to receive said spring, a gear on said shaft adapted to receive the other end of said spring, a friction device feather-keyed to said shaft, said device co-operating with a face of said gear to form a friction clutch, and means for limiting the compression of the spring.
18. In apparatus of the class described, in combination, a shaft, a gear thereon provided with an end face, a friction device feather-keyed to the shaft and co-operating with said face to form a friction clutch, means opposing the movement of the gear axially of the shaft in a direction to reduce the torque of the clutch, and means oper-

8
ative to move the friction device axially of the shaft in a direction to increase the torque of the clutch.

19. In apparatus of the class described, in combination, a shaft, a member thereon provided with an end face, a friction device feather-keyed to the shaft and coöperating with said face to form a friction clutch, means opposing the movement of said member axially of the shaft in a direction to reduce the torque of the clutch, and means maintaining normally a predetermined torque and permitting a movement of the friction device axially of the shaft in a direction to increase the torque of the clutch.

20. In apparatus of the class described, in combination, a motor, a pinion internally threaded and driven thereby, a driving connection between motor and pinion comprising a threaded shaft on which the pinion is mounted for rotation and axial movement, a gear, the pinion moving axially into engagement with the gear when the shaft is rotated, the shaft moving axially if the pinion teeth and gear teeth meet end to end, an elongated bearing for the shaft to permit said axial movement thereof, a compression spring opposing said axial movement, and a seat for said spring outside the bearing, a portion of the length of the spring surrounding said elongated bearing.

21. In apparatus of the class described, in combination, a motor, a gear driven thereby, a shaft, a spring surrounding said shaft, a gear meshing with said first gear provided with a face and internally recessed to receive said spring, a friction device feather-keyed to the shaft and coöperating with said face to form a friction clutch for transmitting motion from the motor to the shaft, a pinion threaded on a portion of said shaft and adapted to move axially toward the motor into mesh with a gear, the axial movement of the pinion serving to compress said spring and tighten said clutch, means for limiting the compression of the spring to limit the torque of said clutch, and a second spring opposing axial movement of the shaft, the pinion effecting the axial movement of the shaft and thereby the rotation of said pinion if the pinion teeth and the teeth of said last-named gear meet end to end.

22. In apparatus of the class described, in

combination, a motor, a pinion driven thereby, a driving connection between motor and pinion comprising a shaft externally threaded and coöperating with internal threads on the pinion, whereby the pinion may rotate and move axially with respect to the shaft, and impositive holding means having a plane surface coöperating with a face of said pinion for retaining the pinion in its position of rest axially of the shaft, to prevent accidental rotation of the pinion when the shaft is stationary.

23. In an engine starter, the combination with a driven gear, of a shaft having threads, a member comprising a gear teeth portion for coöperation with said driven gear and a threaded portion for coöperation with said threads of said shaft to cause automatic shifting of said member into mesh with said driven gear, means for impositively holding said member in home position, said means including a stop on said shaft and a part movable with said member, said stop and part having coöperating plane impact surfaces.

24. In an engine starter, the combination with a driven gear, of a shaft, a driving gear thereon adapted to be brought into mesh with said driven gear and to be automatically demeshed upon starting of the engine, means for impositively holding said driving gear in demeshed position, said means including a slidable stop on said shaft, a part movable with said gear, said stop and part having coöperating plane impact surfaces normal to the shaft and a coil spring to take the shock of impact.

25. In an engine starter, the combination with a driven gear, of a shaft, a driving gear thereon adapted to be brought into mesh with said driven gear and to be automatically demeshed upon starting of the engine, means for impositively holding said driving gear in demeshed position, said means including a slidable stop on said shaft and a part movable with said gear, said stop and part having coöperating plane impact surfaces normal to the shaft, and a compression spring back of said stop and encircling said shaft to take the shock of impact.

In testimony whereof I have signed my name to this specification this 19th day of July, 1916.

LIONEL M. WOLFFSOHN.
